[57] CLAIM

The ornamental design for a handpowered pallet truck, as shown and described.

DESCRIPTION

FIG. 1 is an isometric view from the front, top and one side of a handpowered pallet truck showing my new design;

FIG. 2 is a top plan view thereof;

FIG. 3 is a bottom plan view thereof; and,

FIG. 4 is a front elevational view thereof.

The opposite side elevational views are mirror images.
